Assistant Examiner — Arva P Adams

(57) **CLAIM**

The ornamental design for a water filter jug, as shown and described.

DESCRIPTION

1. Lid for jars
2. Water filter jug
3. Water filter jug
4. Water filter jug
- 2.1 : Perspective
- 2.2 : Right
- 2.3 : Left
- 2.4 : Top
- 2.5 : Bottom
- 2.6 : Front
- 2.7 : Back
- 3.1 : Perspective
- 3.2 : Right
- 3.3 : Left
- 3.4 : Top
- 3.5 : Bottom
- 3.6 : Front
- 3.7 : Back
- 4.1 : Perspective
- 4.2 : Right

(Continued)

(Continued)

4.3 : Left

4.4 : Top

4.5 : Bottom

4.6 : Front

4.7 : Back

1 Claim, 18 Drawing Sheets
